(57) **CLAIM**

The ornamental design of a geomatics instrument carrier, as shown and described.

DESCRIPTION

FIG. 1 is a perspective front, top and left side view of the geomatics instrument carrier showing my design;

FIG. 2 is a front view thereof; the back view, is a mirror image;

FIG. 3 is a top view thereof,

FIG. 4 is a right side view thereof; and,

FIG. 5 is a left side view thereof.

The broken lines disclosure in FIGS. 1 and 2 depict environmental matter and forms no part of the design.
